CLAIM

The ornamental design for a container, as shown and described.

DESCRIPTION

FIG. 1 is a perspective view of my new container.

FIG. 2 is a side view of the container; and,

FIG. 3 is a bottom view of the container.

My container is characterized by an open top; and a centrally located hollow column which is oval in cross section, close at the top and open at the bottom, and is attached to the bottom panel of the container.
